Des. 208,190
Patented Aug. 1, 1967

208,190

HAND HELD SCRAPER

Robert D. Parry, 7240 Algonquin Drive,
Cincinnati, Ohio 45243

Filed June 3, 1966, Ser. No. 2,542

Term of patent 14 years

(Cl. D9—6)

FIGURE 1 is a side elevational view of a hand held scraper showing my new design.

FIGURE 2 is an elevational view illustrating the side opposite that of FIGURE 1.

FIGURE 3 is a top plan view thereof.

FIGURE 4 is a bottom plan view thereof.

FIGURE 5 is a cross-sectional view taken on the line 5—5 of FIGURE 2.

FIGURE 6 is an end elevational view.

FIGURE 7 is an elevational view of the end opposite that shown in FIGURE 6.

FIGURE 8 is a cross-sectional view taken on the line 8—8 of FIGURE 1.

I claim:

The ornamental design for a hand held scraper, substantially as shown and described.
